AUTOMATIC ELEVATOR FOR DRYER

Edward A. Heckman, Allentown, and Walter J. Tesche, Coopersburg, Pa., assignors to Western Electric Company, Incorporated, New York, N. Y., a corporation of New York

Application June 12, 1953, Serial No. 361,114

5 Claims. (Cl. 34—45)

This invention relates to an automatic elevator system and particularly to an elevator system wherein the elevator carriage automatically makes a number of timed stops.

The removal of moisture from articles by using commercial dryers, such as those employing boiling tetrachlorethylene, involves the manual operations of lowering the water-wet articles into the boiling tetrachlorethylene tank at the bottom of the dryer for a prescribed period of time, raising the tetrachlorethylene soaked articles to a vapor region above the tank and holding them there for another prescribed period of time and finally raising them above the vapor region where they are held for another period of time to allow any condensed tetrachlorethylene to evaporate, after which the dried articles are removed from the dryer.

It is the general object of this invention to provide an elevator system for eliminating the aforementioned manual operations that will automatically and sequentially control the positioning of an elevator carriage and hold the carriage at its stops for fixed time intervals.

A preferred embodiment of the invention utilizes an automatic elevator system wherein the carriage is suspended from a motor driven sprocket, a plurality of limit switches disposed around the sprocket and their associated circuits control the carriage drive motor to sequentially position and hold the elevator carriage for fixed time periods at the different elevations as required for the operation.

These and other features of the invention will be more fully understood from the following detailed description taken in conjunction with the accompanying drawing in which:

Fig. 1 is a partially broken, elevational view of an elevator system according to the invention adapted to a commercial tetrachlorethylene dryer;

Fig. 2 is a detailed view of the chain sprocket and the limit switches of the device of Fig. 1, as seen from the backside of the sprocket of Fig. 1; and

Fig. 3 is a schematic diagram of the control circuit of the elevator of Fig. 1.

Referring now to Fig. 1, a commercial tetrachlorethylene dryer 4 is provided with an elevator carriage 5, shown schematically as a box but which may be of any construction convenient for carrying the articles to be dried, an elevator drive 6 and a control panel 7. The adjustable timers of the time delay relays, the control push button switches and the "on" lamp are mounted on the control panel 7. The elevator carriage 5 slides up and down in the dryer 4 on the guide rods 8 and 48 and is suspended from a sprocket 9 by a chain 10. The sprocket 9 is driven by motor 11 through a gear reduction unit 12.

As shown in Fig. 2, three limit switches 13, 14 and 15 are mounted on the cover plate 18 for the elevator drive 6 and are disposed around the sprocket 9 which is provided with a pin 16 for actuating switches 13 and 15 and a cam 17 for actuating switch 14.

Before discussing the control circuit for the system, the operation of switch 14 will be described. When the elevator carriage 5 is being lowered and the sprocket 9, as seen in Fig. 2, rotates clockwise, the flat side 19 of cam 17 engages roller 20 of switch 14 which is free to pivot counterclockwise about 21 as shown in phantom so that the cam 17 passes without actuating the switch 14 and the roller 20 is returned by a spring to the position shown. As the elevator carriage is moved up, and the sprocket 9 rotates counterclockwise, the inclined surface 39 of the cam engages the roller 20 and forces it outward radially of the sprocket 9 thereby operating switch 14.

Referring now to the circuit diagram of Fig. 3, the operation of the system will be described. After the articles to be dried have been placed on the elevator carriage 5 shown in its start or loading position 60 (Fig. 1), the "down" button 22 is pushed, closing contacts 31 to energize the "down" drive control relay 26 from the power source 23 through the normally closed contacts 27 of switch 13 thereby starting the motor 11 by connecting it to the power source 23 through the contacts 24 and 25 of relay 26 to lower the elevator carriage 5. Lock-up contacts 30 are provided on relay 26 so that only a momentary energization is required to hold the relay 26 operated. The operation of the "down" button also momentarily opens the "up" circuit at contacts 43 to release the "up" drive control relay 42 in the event that it is in a locked-up condition otherwise the source 23 would be short circuited if the contacts 40 and 41 were closed when contacts 24 and 25 closed.

As the motor 11 turns the sprocket 9 to lower the elevator carriage from the starting position 60 shown in Fig. 1, switch 15 is released to prepare the "up" circuit by closing contacts 32, contacts 50 being opened to de-energize the end of cycle timer 33 which closes its contacts 38 to energize the "on" lamp 34 indicating the drying cycle has been started.

As the sprocket 9 continues to turn in the "down" direction, cam 17 engages the roller 20 of switch 14, but as previously described, the switch 14 is not actuated. When the elevator carriage has been lowered to the bath position 35 (Fig. 1), it is stopped when pin 16 on the sprocket 9 actuates switch 13 whose contacts 27 open the motor energizing circuit by de-energizing the "down" drive control relay 26 to open contacts 24 and 25. Contacts 36 of switch 13 close to complete the energizing circuit for time delay relay 37. After its fixed time interval, relay 37 operates to close contacts 38 to energize the "up" drive control relay 42 through the closed contacts 32 of switch 15. Contacts 40 and 41 of the motor energizing circuit close to connect the motor to the A. C. source 23, the polarity being reversed from that applied to the motor for driving the elevator carriage down. The motor thereupon drives the elevator up releasing switch 13 and opening contacts 36 thereon to de-energize time delay relay 37 which then opens its contacts 38. Relay 42, however, remains energized through contacts 32 of released switch 15, normally closed contacts 53 of switch 14 and lock-up contacts 52 of relay 42.

When the rising elevator reaches position 51 (Fig. 1) in the vapor region of the dryer, cam 17 on the sprocket 9 actuates switch 14. Contacts 53 of switch 14 thereupon open and de-energize relay 42 opening contacts 40 and 41 to de-energize the motor. Time delay relay 55 is energized through contacts 54 of switch 14 and after its fixed time interval, contacts 56 close thereby energizing relay 57. Relay 42 is re-energized through the closed contacts 58 of relay 57 which re-starts the motor 11 to drive the elevator carriage up again. Switch 14 is there-

upon released de-energizing time delay relay 55, but relay 57 remains energized through its lock-up contacts 59.

When the elevator returns to the starting position 60 (Fig. 1), pin 16 on the sprocket 9 actuates switch 15 opening contacts 32 to de-energize relays 57 and 42 thereby opening the motor energizing circuit at contacts 40 and 41. Time delay relay 33 is energized through contacts 50 of switch 15 which, after its fixed time delay interval, opens contacts 38 to extinguish lamp 34 indicating that the articles in the elevator carriage are dry and may be removed.

Besides the automatic features of the invention, for convenience or emergency purposes, manual "stop" and "up" controls are provided on the control panel 7. When pressed, the "stop" button 61 opens the energizing circuits or the "up" and "down" drive control relays 42 and 26. When the "up" button 29 is pressed, contacts 28 are opened to de-energize the "down" drive control relay 26 and contact 62 of the "up" button closes the energizing circuit for the "up" drive control drive control relay 42.

The time delay relays used in this circuit, mounted on the control panel 7, are of a commercially available type having adjustable timers whereby the desired time in bath, time in vapor and final evaporation time may be set.

It is to be understood that the above described arrangements are simply illustrative of the application of the principles of the invention. Numerous other arrangements may be readily devised by those skilled in the art which will embody the principles of the invention and fall within the spirit and scope thereof.

What is claimed is:

1. An elevator system for an article dryer having a bath region, a vapor region above the bath region and an evaporation region above the vapor region said system comprising a carrier for the articles, a sprocket, a rotary driver for the sprocket, means for supporting the carrier from the sprocket, a plurality of switches disposed around and controlled by the sprocket, a relay, means for controlling the relay to start the driver to lower the carrier to the bath region, means controlled by the switches for reversing the rotation of the driver to raise the carrier from the bath region through the vapor and evaporation

regions and time delay relays controlled by the switches for sequentially stopping the driver to hold the carrier for predetermined and independently timed stops in the bath, vapor and evaporation regions.

- 5 2. A system for automatically and sequentially controlling the positioning of an elevator carriage comprising a rotatable member, a driver for the member, means for supporting the carriage from the member, a plurality of switches positioned to be operated in sequence by the rotating member, means for starting the driver to lower the carriage, means controlled by one of the switches for stopping the carriage in a given lowered position and initiating a timing cycle, means effective at the end of said cycle for starting the driver to raise the carriage and means controlled by another of the switches for stopping the upward travel of the carriage at an intermediate position.
- 10 3. An automatic system according to claim 2 in which manually controlled switching means are provided for stopping the driver at any position for the carriage and 20 other manually controlled switching means are provided for interrupting the sequential positioning of the carriage and causing the driver to raise the carriage.
- 15 4. The combination with a rotatable member a carriage, means for supporting the carriage from the member and driving means for selectively rotating the member in opposite directions to lower and raise the carriage, of relays for controlling the rotation of the member, timing devices for disabling the driving means for predetermined time intervals and switches actuated by the member in 30 different positions thereof for selectively energizing the timing devices.

- 25 5. A system according to claim 4 in which one of the switches is adapted to be actuated only when the member is rotating in one direction to cause the carriage to stop 35 at a predetermined position only when it is moving in a particular direction.
